UNITED STATES PATENT OFFICE.

ELMER FLETCHER, OF CHICAGO, ILLINOIS, ASSIGNOR TO FLETCHER WORKS CO., OF CHICAGO, ILLINOIS, A CORPORATION OF ILLINOIS.

SOUND-BOX.

1,331,864.

Specification of Letters Patent. Patented Feb. 24, 1920.

Original application filed November 2, 1917, Serial No. 199,807. Divided and this application filed July 12, 1918. Serial No. 244,643.

To all whom it may concern:

Be it known that I, ELMER FLETCHER, a citizen of the United States, and a resident of Chicago, in the county of Cook and State 5 of Illinois, have invented certain new and useful Improvements in Sound-Boxes, of which the following is a full, clear, and exact description.

The invention relates to sound boxes.

10 The object of the present invention is to provide an improved connection between the needle support and the sound box. This application is a division of Serial No. 199,807, filed Nov. 2, 1917.

15 The invention consists in the several novel features hereinafter set forth and more particularly defined by claims at the conclusion hereof.

20 In the drawings: Figure 1 is a side elevation of a sound box provided with the invention. Fig. 2 is a transverse section. Fig. 3 is a longitudinal section. Fig. 4 is a detailed perspective showing the parts of the improved pivotal connection separated from 25 one another.

25 The instrument comprises a sound box 7 provided with any suitable chamber and a diaphragm 9 which is held therein in any suitable manner, as well understood in the 30 art, so that the diaphragm may be vibrated responsively to movements imparted to the needle by a record or vice versa. The sound box is formed with a pair of bearing lugs 25 provided with transversely extending 35 alined knife-edged projecting ribs 26 which are adapted to form a fulcrum for the needle support. These lugs 25 are spaced apart and the bearing edges of the lugs 26 are adapted to extend into V-shaped notches 27 formed 40 in a plate-like needle support 16 which is provided with a lug 17 which is connected to the diaphragm by an arm 18'. A needle-socket 14 is formed on the supporting plate 16 and is adapted to receive the needle 15. 45 The ribs 26 are alined with each other and spaced apart to form a knife-edged pivotal fulcrum at the sides of the needle support respectively, and one which will minimize frictional resistance to the pivotal movements of the support.

50 The support 16 is yieldingly held in position by a pair of wire clips 24, each of which is provided with an inwardly extend-

ing arm or member 28 adapted to enter and be removably held in a socket 29 formed in the outer side of one of the lugs 25, and an arm or member 30 adapted to underlie the support 16 in substantial transverse alinement with the knife-edged bearing and an upturned terminal 31 adapted to enter a socket in the underside of the support 16 and to hold the terminal spaced from the support. These terminals also serve to yieldingly hold the support against movement in the direction of the knife-edge bearings. Each clip 24 is formed of spring wire so that it will yieldingly hold the fulcrum members 26 and 27 in engaged relation. The sockets 29 are of sufficient length to prevent lateral movement of clip-members 28. In 70 practice, the arm 18' is usually fixed to the diaphragm at the factory, so that in event replacement of a diaphragm is necessary, the needle support must be removed with it. These spring clips permit ready removal and replacement of the diaphragm and its arm. To release the support, it is only necessary to spring the arms 30 downwardly sufficiently to withdraw the terminals 31 from the seats 32 and then swing the clips laterally 75 to clear the support or withdraw the clip-members 28 from their sockets.

75 This connection exemplifies a sound-box in which there are knife-edge bearings between the needle support and the sound box to minimize frictional resistance and by reason of their length, as contra-distinguished from points, the bearings will be durable and efficient. Also one in which the pressure is applied in substantial alinement with the knife 80 edges and in such manner that the pressure will not materially resist the pivotal movement of the needle support. By employing wire clips, as distinguished from flat springs, the pressure is applied to the needle support 85 and to the sound box in substantial alinement with the knife-edge bearings which are of considerable length so that wear will be avoided and there will be no substantial retardation of the pivotal movement of the 90 needle support by the spring clips.

95 In practice, it has been found that this connection results in efficient conduction of the vibrations to the diaphragm.

100 The invention is not to be understood as restricted to the details set forth, since these

may be modified within the scope of the appended claims, without departing from the spirit and scope of the invention.

Having thus described the invention, what I claim as new and desire to secure by Letters Patent, is:

1. In a sound box, the combination of a case, a diaphragm in the case, a needle-support connected to the diaphragm, said support and case being provided with transversely extending knife-edge ribs and grooves between them to form a transversely extending fulcrum, and spring clips for yieldingly and removably holding the support and case in engaged relation at said bearings, having integral members interfitting with and engaging the case and support only at points in the plane of said knife-edges.
2. In a sound box, the combination of a case, a diaphragm in said case, a needle-support connected to the diaphragm, alined fulcrum bearings between the support and the case, and a pair of spring wire clips, the case

and the support being provided respectively with sockets in which the terminals of the clips are removably self-retained.

3. In a sound box, the combination of a case, a diaphragm in said case, a needle support connected to the diaphragm, alined knife-edge bearings between the support and the case, and a pair of spring wire clips, the case and the support being provided respectively with sockets in the plane of the knife-edges and in which the terminals of the clips are removably self-retained.

4. In a sound box, the combination of a case, a diaphragm in said case, a needle support connected to the diaphragm, alined knife-edge bearings between the support and the case, and a pair of spring wire clips, each provided with a pair of inwardly extending arms, the case being provided with outwardly open sockets to receive one arm of the clips, the support having seats in its underside, the other arms of the clips having terminals yieldingly held in said seats.

ELMER FLETCHER.
